(57) **CLAIM**

The ornamental design for a cushion for a mask, as shown and described.

DESCRIPTION

FIG. 1 is a rear perspective view of a cushion for a mask according to an embodiment of our design;
FIG. 2 is a top view thereof;
FIG. 3 is a bottom view thereof;
FIG. 4 is a front view thereof;
FIG. 5 is a rear view thereof;
FIG. 6 is a left side view thereof with the right side view being a mirror image;
FIG. 7 is a front perspective view thereof;
FIG. 8 is a rear perspective view of a cushion for a mask according to an embodiment of our design;
FIG. 9 is a top view thereof;
FIG. 10 is a bottom view thereof;
FIG. 11 is a front view thereof;
FIG. 12 is a rear view thereof;
FIG. 13 is a left side view thereof with the right side view being a mirror image;
FIG. 14 is a front perspective view thereof;
FIG. 15 is a rear perspective view of a cushion for a mask according to an embodiment of our design;
FIG. 16 is a top view thereof;
FIG. 17 is a bottom view thereof;
FIG. 18 is a front view thereof;
FIG. 19 is a rear view thereof;
FIG. 20 is a left side view thereof with the right side view being a mirror image; and,
FIG. 21 is a front perspective view thereof.
